[57] CLAIM

The ornamental design for an arm exerciser, as shown
and described.

DESCRIPTION

FIG. 1 is a front perspective view of an arm exerciser
showing my new design;
FIG. 2 is a top plan view thereof;
FIG. 3 is a front elevational view thereof;
FIG. 4 is a rear elevational view thereof;
FIG. 5 is a side elevational view thereof;
FIG. 6 is a side elevational view of the side opposite
that shown in FIG. 5;
FIG. 7 is a front perspective view of a modified form of
the design shown in FIGS. 1 through 6; and,
FIG. 8 is a rear perspective view thereof.
